RIDEABLE BOUNCING TOY

Bryan F. Nicholls, Northampton, England, assignor to
The Metloy Company Limited, London, England

Filed Oct. 28, 1968, Ser. No. 14,196

Claims priority, application Great Britain May 3, 1968

Term of patent 14 years

Int. Cl. D21—04

U.S. Cl. D34—15

FIG.1.

FIG.2.

FIG. 3.

FIGURE 1 is a front elevational view of a rideable bouncing toy showing my new design;

FIGURE 2 is a top plan view of FIG. 1; and

FIGURE 3 is a side elevational view of FIG. 1, the opposite side being substantially identical.

I claim:

The ornamental design for a rideable bouncing toy, as shown and described.
